UNITED STATES PATENT OFFICE

2,503,631

LOCOMOTIVE TENDER WATERING DEVICE

James E. O'Brien, Cleveland, Ohio

Application October 23, 1944, Serial No. 560,080

3 Claims. (Cl. 137—21)

1

This invention is directed to locomotive watering towers and the general object is to provide an engine tender watering apparatus which can be quickly manipulated and conditioned to discharge water into the tender manhole by the fireman or other attendant when the locomotive has been stopped at a spot position and regardless of the type and size of the locomotive tender.

As regards the matter of locomotive tenders, those of present day railroad equipment present a wide range in length and height which has presented a serious problem in delivering liquid into the hatches of the tenders unless the hatch is spotted in an accurate position relative to the water delivery fixture to permit of entering the liquid delivery spout or nozzle into the hatch.

For example, water delivery fixtures, as hitherto provided, had neither sufficient range nor flexibility to permit of supplying water to the various classes of tenders without moving the locomotives from coaling position because the water delivery fixture would not be manipulated to permit of entering the delivery nozzle into the hatch.

Furthermore, all liquid delivery fixtures for railroad service as hitherto provided have been arranged to swivel horizontally in circles toward and from the center line of the track from a pivot located adjacent to the track. This confined the range of the spout nozzle over the hatch opening to close limits depending upon the radius of the horizontal swivel circle. Such an arrangement necessitated the manipulation of a long spout, hinged or otherwise connected from the pivoted pipe, with resulting unwieldiness due to insufficient flexibility in manipulating the spout to enter the hatch unless the hatch is spotted accurately. These objectionable features have been particularly evident in the liquid delivery fixtures pivoted to overhead supply piping above shipping clearance between the tracks such as those usually provided above the main tracks at coaling plants to supply liquid and fuel to tenders at the same location.

All watering devices pivoted to overhead supply lines above tracks, as hitherto provided, have had long spouts hinged at high elevations above shipment clearances. These long, heavy spouts require heavy counterweights with ropes over pulleys which develop various angles of rope pull at various stresses requiring great effort to pull the spout down and swing it around, resulting in danger to personal safety of the operator.

The principal object of my invention is to provide a liquid delivery fixture with sufficient range,

2

flexibility, accuracy and ease of manipulation to assure delivery of water to tenders of various lengths and heights without moving the tender from coaling position and to provide a fixture which will swing parallel to the track and remain the same distance from the center line of the track throughout the entire swing range of the swivel pipe.

Another object of my invention is to provide a device which can be manipulated to place a short spout almost directly above the hatch of the tender so that the fireman or other employee, standing on the tender adjacent to the hatch, can reach the spout and enter it into the hatch easily and safely by means of handles attached to the spout.

Another object is to provide a spout counterweight rope arrangement which remains always parallel with the swing pipe to maintain uniform alignment and stress of rope and uniform ease of handling the spout throughout the entire range of the device.

Another object is to provide a device arranged so that a swivel ball bearing housing can be insulated and heated and thereby be maintained in operative condition regardless of outside temperatures.

Another object is the provision of a locomotive watering apparatus or tower having such structural and operating characteristics that the locomotive can be water serviced quite rapidly while standing on the high speed or main line track of a railroad and, if desired, while the locomotive tender is being coaled.

A further object of the present invention is the provision of a locomotive water tower structure which will remain serviceable in the discharge of a large volume of water in a short period of time under varying weather conditions.

A still further object of this invention is the provision of a plurality of articulated conduits of large volumetric capacity joined in such manner that the discharging conduits can be swung downwardly from an overhead position to the water hole of the engine tender with a minimum of physical effort and remain thus without being held by the fireman or attendant.

To the accomplishment of the foregoing and related ends, said invention, then, consists of the means hereinafter fully described and particularly pointed out in the claims; the annexed drawings and the following description setting forth in detail certain structure embodying the invention, such disclosed structure constituting, however, but one of various structural forms in

which the principle of the invention may be used.

In said annexed drawings:

Fig. 1 is a track side elevational view of a water tower mechanism embodying the features of my invention;

Fig. 2 is an elevational view of the water servicing apparatus as viewed longitudinally of the tracks;

Fig. 3 is an enlarged view of a swingable down pipe comprising one of the essential elements of the mechanism;

Fig. 4 is a cross-sectional view taken substantially along the line 4—4, Fig. 3;

Fig. 5 is a track side elevational view of a modified form of an adjustable mounting attached to the down pipe for the water spout or funnel;

Fig. 6 is an enlarged detail view of part of the down pipe suspension means for pivotally supporting the down pipe of the apparatus;

Fig. 7 is a detail view of a swivel hinge bolt with radial bolt roller and shaft comprising part of the spout mounting mechanism shown in Fig. 5;

Fig. 8 is an enlarged cross-sectional view taken substantially along the line 8—8 of Fig. 2 through part of the swivel suspending means for the down pipe;

Fig. 9 is a view in section taken on line 9—9 of Fig. 8;

Fig. 10 is a view in elevation taken on line 10—10 of Fig. 1, the view being on a larger scale;

Fig. 11 illustrates a modified water funnel or spout construction comprising two telescopic members; and

Fig. 12 is a cross-sectional view of the spout construction shown in Fig. 11 and taken substantially along the line 12—12 of Fig. 11.

It is contemplated that the present invention on an improved water servicing apparatus for locomotives can be used, if desired, with such a coaling station for the general arrangement of the cooperating elements is such that the watering of the engine tender can be effected without interfering with the coaling operations and without necessitating respotting of the locomotive. The tender may be coaled and watered simultaneously at one spot with these facilities.

In the present disclosure reference is made to a tower structure disposed above or overhanging the main track and it is to be understood that such superstructure as may comprise part of the present invention will be either part of the coaling tower structure or a separate overhead structure as desired.

Referring to Fig. 1 of the drawings, the superstructure or tower structure is merely represented here as an overhead platform, generally indicated by the reference character P, and the various means for suspending the swingable water pipe and spout or funnel are fixed to and partly supported by the platform structure.

The water servicing mechanism comprises a substantially horizontally disposed conduit or pipe 15 leading from a water source and a valve mechanism (not shown) to a swingable elbow conduit mechanism, generally indicated in Fig. 2 by the reference numeral 16, and from which depends a down pipe 17 terminating in an offset lower end 17a. An adjustable spout or funnel structure 18 is pivotally suspended on the down pipe for rapid and convenient connection to, and disconnection from, the offset end of the down pipe for purposes to be described.

Before further description of the details of construction and manipulation of the various means associated with the essential elements already referred to, it is desired to direct attention to the varying conditions of operation which must be met due to variations in the elevation and location of the watering holes of various types and designs of engine tenders present in the locomotive equipment of most railroads. In Fig. 1 five different engine tender water ports are diagrammatically indicated at positions A, B, C, D and E. By having the down pipe 17 and its offset discharge mounted to be swingable in a vertical plane extending substantially parallel to the railroad tracks and by having the funnel or spout 18 extend outwardly and downwardly from the offset end of the swingable down pipe, an approximate positioning of the down pipe and spout can be effected by the fireman or attendant while the spout is in an upwardly folded position on the down pipe. Such a spout position is shown by the dotted lines in Fig. 2. Counterweighting means to maintain the spout in such folded position at all times, except when a tender is being serviced, is provided and hereinafter will be described. Also the spout may be of a telescopic construction when the variations in water hole location are relatively great.

Referring to Fig. 2 it will be seen that the substantially horizontally disposed conduit 15 is attached by straps 22 to the under side of the platform structure P. The elbow 16, comprising the conduit connection between the pipe 15 and down pipe 17, has a swivel connection with the end 30 of the pipe 15 and this swivel construction is shown in cross-section in Fig. 8. Also the elbow structure 16 has a front pivotal support comprising a stub shaft 35 (see Fig. 6) secured to the plate 36, the plate 36 being riveted to a front wall 37 of the elbow structure 16. The stub shaft 35 may be supported by a bearing box 38 attached to a bracket on the under side of the platform P and is of sufficient length to extend beyond bearing box 38 and to this extension 40 thereof a counterbalancing lever 40 is keyed. The lever 40 carries adjustable counterweights 41 and 42 held in the desired counterbalancing position in any convenient manner, as for example by bolts as indicated in Fig. 2. To the hub of the 45 counterweight lever 40 is attached a support 43 for a pair of small sheaves 44 shown on Fig. 1 which serve as a guide for a spout counterweight rope or cable, as will be described.

The swivel connection between the elbow 16 and horizontal pipe 15, as shown in cross-sectional detail in Fig. 8, comprises a housed lubricant and water-tight ball bearing swivel mounting for the elbow structure 16. Hence, attached to the flanged end 15a of the horizontal pipe 15 is a flanged bearing housing 46 with split housing cap 47 which supports outer ball bearing race ring 48 which bears ball members 49. Split flanged cap 47 is secured to the flange of housing 46 by means of bolts through holes 47a and the halves of split cap 47 are secured together by bolts through holes 47b. The bearing ring 48 is disposed within the flanged annular housing comprised of members 46 and 47. The housing closure 46 and clamping ring 47 hold the ring 48 in a properly fixed relation to the housing. The flanged bearing sleeve 50, which is disposed within the housing 46 and 47, comprises an extension of elbow structure 16 and revolves on ball members 49.

To prevent the flowing water from direct contact with the swivel structure, a stationary inner

sleeve 51 flanged on one end is provided, with its flange clamped water tight between the flanges of water supply pipe 15 and bearing housing 46. The sleeve 51 has an internal diameter substantially equal to the internal diameter of the water pipe 15. This sleeve 51 is arranged in abutting relation to the flanged end of the pipe 15 and at its other end in abutting relation to the flanged end of the elbow structure 16. This stationary sleeve 51 comprises an extension of pipe conduit 15 to deliver the water into elbow structure 16.

Non-freezing and water-resisting grease is charged into the interior of housing 46 through fittings in grease holes 46a and 47c by means of grease gun or other grease applying means to lubricate the rotating members 49 and 50.

The grease is retained and sealed in the ball bearing compartment by means of annular spring actuated seal 52 and annular felt seal 53. Spring actuated seal 52 is fitted into counterbore in the end of rotating sleeve 50 and around sleeve 51 in such manner as to permit free rotation of sleeve 50 while preventing escape of grease from the ball bearing compartment and preventing entrance of water into the ball bearing compartment through the annular space between sleeves 50 and 51. Felt seal 53 is fitted into counterbore in annular split cap 47 in such manner as to permit free rotation of sleeve 50 while preventing escape of grease from the ball bearing compartment through the annular space between sleeve 50 and cap 47. Radial slots 50a are formed in the end of member 50 adjacent the housing 46 wall for admitting grease to the seal 52.

As described, the weight of the down pipe 17 and the supporting spout is counterbalanced about the center line of the stub shaft 35 and ball bearing structure described by the counterweights 41, 42, whereby, due to the counterweight adjustment on lever 40, the down pipe may be swung and retained by the counterweights in a substantially horizontal track clearing position, as shown by the dotted lines in Fig. 1, in which the pipe is disposed immediately beneath the platform structure P. A stop 69a is provided for positioning the down pipe in the horizontal position and, preferably, the stop comprises a bracket secured to platform P, which bracket includes a horizontal spring supported member that is engaged by the counterweight lever when the drop pipe is raised to the horizontal position above shipment clearances. Also, I prefer to provide a locking device 61 that is attached to the under side of the platform structure by a bracket 60, which device prevents the spout 18 from inadvertently swinging outwardly from the down pipe and over the track when the down pipe is in the raised position.

To facilitate the manipulation of the water spout or funnel I provide a holding means for maintaining the down pipe in any of its swung or approximated positions whereby the fireman will have both hands free to manipulate the spout. This holding means may comprise an arcuate member 70 supported by angle irons 71 and 72, the latter being secured to the superstructure P with the center of the arc of the member 70 corresponding substantially to the pivotal center of the swingable down pipe. I provide a hand rope 76 by which the operator may swing the down pipe to vertical. The rope 76 is reeved through pulley 77 that is secured to the housing strut member by bracket 78, and attached to the end of drop pipe counterweight lever 40 by means of clevis 79. A bracket 81 is secured to the outer end of lever 40, and the bracket includes a laterally extending

portion that overhangs the member 70. A pin or plunger 80 is extendable through an opening through the laterally extending portion of bracket 81 and into any one of a plurality of closely spaced holes 70a formed in the member 70. The pin 80 is attached to bracket 81 by a chain, and it may be operated by an attendant on the platform or, if desired, the pin may be mechanically urged to a locking position with member 70 and retracted therefrom by operation of a hand lever and rope, as will be hereinafter described. A rope 82 is attached at one end to the down spout structure and the other end is attached to the water supply valve mechanism in line 15 (not shown) so that the water supply may be controlled from the tender or from the platform structure P. When the down pipe is being swung by the operator pin 80 is out of contact with the member 70 and when it is desired to lock the down pipe in any swing position the pin may be inserted in the nearest of the perforations 70a formed in the member 70. The centers of these perforations are indicated by the center lines in Fig. 1.

The funnel or water spout structure is of such shape as to be swung conveniently into connecting relation to the offset end 17a of the down pipe and is of such shape that the hydraulic reactions of the water being discharged thereto from the down pipe will not cause up or back flow or creeping movement of the spout.

In Figs. 1, 11 and 12 the spout structure is shown as comprising two telescopically arranged inner and outer tubular members 82a and 83 respectively, which slide relatively upon rods 84 fixed to the inner member 82a. An arm structure 99, secured to the spout structure at the pivoted end thereof, is formed by two spaced apart flat iron members 99a and 99b. One of the spacer bolts 99c carries a chain 99d, the free end of which is detachably connected to the outer telescopic member 83 at a handle formation 16c. The fireman can extend the overall length of the spout structure by unlatching the chain and then relatching it, as will be obvious.

It will be noted in Figs. 1, 2, 5 and 11 that the water spout is of a funnel shape with the upper end 18a thereof considerably larger than the offset lower end or portion 17a of the down pipe, and the body of the funnel tapers to an elbow nozzle formation 18b. The general shape shown and described affords a structure which is not reactively affected by a larger volume of water discharging therethrough in a short period of time, due to the broad bellied design of 18a which holds a large quantity of the water being delivered, which tends to hold the spout down in the hatch. The funnel may be pivotally suspended on the down pipe in various ways and in Figs. 5 and 7 this is done by a bracket structure 89 which supports a bail or stirrup 90. Through the stirrup 90 a sheave or roller carrying pivotal bolt 91 is supported by an attaching means comprising a nut 92 and bearing washer 93, see Figs. 5 and 7. The pivotal bolt 91 has the lower end thereof forked to receive a grooved roller 94 to roll on bolt or pin 94a. Radial hinge bolt 95 attached to brackets 96 fixed to the funnel structure, slides on the grooved roller 94. A relative adjustment between the offset end 17a of the down pipe 17 and the funnel in angular directions on either side of a median plane passing through the pivotal axis of the down pipe and the center of the down pipe can be obtained as indicated by the dotted lines in Fig. 5 so that manipulation of the funnel

relative to the water hole of the tender is possible after the down pipe has been swung to its approximate down position and locked by pin 30. Also it will be noted that such a pivotal suspension of the down spout will permit the down spout to be swung upwardly to the dotted position shown in Fig. 2 when it is desired to swing the down pipe to the upper dotted position shown in Fig. 1. A bracket 98, carried by the down pipe, serves to further support the spout when in a folded up position.

It will be noted in Fig. 1 that the pivotal suspension for the spout is merely a plain hinge construction comprising a pivot pin 75 suitably supported by the bracket 89 on the down pipe. The bars forming the arm 99 in this instance may comprise part of the hinge connection, as shown.

To further the ease of manipulation of the spout or funnel I provide a counterweight means tending to maintain the down spout in an upwardly swung or folded position relative to the down pipe. This may comprise the referred to fixed arm 99, a counterweight cable 100 extending over guiding sheaves 101, 102 carried by the downpipe and the hereinbefore referred to pair of sheaves 44. The cable 100 extends upwardly from sheaves 44 to and over a sheave 103 carried by block 104 fixed to the tower structure P. Counterweights 105 serve to maintain the counterweight cable 100 in the desired taut condition and to hold the spout in upper dotted position in holding bracket 98.

Sheave supporting brackets 43 and 43a, supporting sheaves 101, 102 and 44 for the spout counterweight rope are fixed to the down pipe assembly and arranged to maintain the spout counterweight rope in perfect parallel with the drop pipe and concentric with the down pipe pivot, regardless of the angle at which the drop pipe is set. The guide sheaves 101 and 102 guide the rope between the pair of sheaves 44 so that the rope rests in the groove of either sheave 44 concentric with the axis of the drop pipe. This arrangement permits of counterbalancing the spout so that it will be held in upper position in the holding bracket 98 when empty but will remain in down position by the weight of the water when delivering water to the tender.

It will be obvious to those skilled in the art that the pipe 15 would have a slight drainage slope relative to the horizontal so that still water would not be present therein during cold weather, when supplied with the usual type water column with self-draining standpipe valve in a pit below ground surface. Also, the character of the swivel connecting means between the elbow structure and the pipe 15 is such that the same may be heated during low temperature weather by electric heating elements arranged thereabout in a housed-in manner.

The entire apparatus may be manipulated by releasing the anchor pin and swinging the dropper with spout down to desired position relative to the tender hatch and re-anchoring. This is done by the fireman or coaling plant attendant from the operating platform. The spout is manipulated to and from the tender hatch from the top of the tender.

The quickest results are obtained at main line coaling stations where a train stops with locomotive tender in coaling position, and a coaling plant attendant swings the device to the fireman who puts the spout into the hatch, opens the valve and fills the tender with water while the coaling plant attendant is coaling the tender.

Those skilled in the art of railroad operation are aware of the fact that the fireman is required to coal and water the locomotive tender at many stations. With devices heretofore provided he must go from the cab of the engine to either the top of the coal pile in the tender or to an operating platform to coal the tender. Then, after the train has been moved and respotted at the water column, he must go from the cab to swing the water column to position relative to the water hatch of the tender and go to the top of the tender to manipulate the spout and water valve.

It will be understood to those skilled in railroad operation that my invention eliminates respotting of the train or locomotive because water and coal may be delivered to the tender at one spotting, regardless of variable lengths and heights of locomotive tenders, considerable time is saved and respotting of equipment is eliminated.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

30 1. In a watering plant for locomotive tenders, an elongated conduit for feeding water to a tender; means for pivotally suspending said conduit above a railroad track whereby said conduit is swingable about one end through an arc located in a vertical plane extending parallel with said track; means connected to said one end of the conduit for supplying water to the conduit; and an extendable spout at the opposite outer end of said conduit for directing water from said conduit into the hatch of a tender, said spout comprising two tubular members telescoped one inside the other, and hinging means for pivotally mounting said spout adjacent the outer end of said conduit whereby said spout may be swung to a position parallel and adjacent to said elongated conduit and to a position in which the spout extends laterally to said conduit, one end of said spout being brought into registry with the outlet of the conduit when in the last mentioned position.

50 2. In a watering plant for locomotive tenders, an elongated conduit for feeding water to a tender; means for pivotally suspending said conduit above a railroad track whereby said conduit is swingable about one end through an arc located in a vertical plane extending parallel with said track; means connected to said one end of the conduit for supplying water to the conduit; and an extendable spout at the opposite outer end of said conduit for directing water from said conduit into the hatch of a tender, said spout comprising two tubular members telescoped one inside the other, hinging means for pivotally mounting said spout adjacent the outer end of said conduit whereby said spout may be swung to a position parallel and adjacent to said elongated conduit and to a position in which the spout extends laterally to said conduit, one end of said spout being brought into registry with the outlet of the conduit when in the last mentioned position, and a counterweight means for said spout comprising a rope suspended by a pulley and having a weight at one end, a sheave structure mounted adjacent to the pivoted end of said conduit, the opposite end of said rope

extending downwardly through said sheave structure and being connected with the spout to tend to rotate the spout about its pivot toward the conduit.

3. In a locomotive watering plant, a water supply pipe extending horizontally, a support structure extending parallel with the pipe and supporting the latter, a down pipe pivotally connected to one end of said pipe by an elbow member, said member being supported on the pipe by an anti-friction bearing, a stub shaft projecting from the outer wall of said elbow member and coaxial with said bearing, a journal carried by said support structure and pivotally supporting said stub shaft, a telescoping spout structure at the outer swinging end of said down pipe and comprising a tubular member telescoped within a second tubular member, said spout structure being pivoted adjacent one end to the down pipe

5

for swinging movement from a position adjacent and parallel with the down pipe to a position extending laterally from the down pipe and in registration with the outlet of the down pipe.

JAMES E. O'BRIEN.
